TABLE

Robert E. Kjer Jakobsen, Los Angeles, Calif., assignor to Schlumberger Limited (Schlumberger N.V.), Houston, Tex., a corporation of the Netherlands Antilles

Filed Feb. 9, 1966, Ser. No. 983

Term of patent 14 years

(Cl. D33—14)

FIG. 1 is an isometrical view of a table embodying my design;

FIG. 2 is a side elevational view of one of the leg units shown in greater detail; and

FIG. 3 is a bottom plan view thereof.

The dominant feature of my design resides in that portion shown in full lines on the drawing.

I claim:

The ornamental design for a table, substantially as shown and described.
